UNITED STATES PATENT OFFICE

ROGER W. ANDREWS, OF ERIE, PENNSYLVANIA, ASSIGNOR TO NORTHERN EQUIPMENT COMPANY, OF ERIE, PENNSYLVANIA, A CORPORATION OF PENNSYLVANIA.

FEEDING WATER TO BOILERS.

1,299,283.

Specification of Letters Patent.

Patented Apr. 1, 1919.

Application filed November 8, 1915. Serial No. 60,455.

To all whom it may concern:

Be it known that I, ROGER W. ANDREWS, a citizen of the United States, residing at Erie, in the county of Erie and State of Pennsylvania, have invented certain new and useful Improvements in Feeding Water to Boilers, of which the following is a specification.

This invention relates to methods and apparatus for controlling the flow of water to boilers, and this application is a continuation of a portion of my copending application, Serial No. 793,159, filed Oct. 3, 1913.

It has also been found in practice that, as boiler capacities increase and increased feed valve capacities are required, the tendency of the valves to stick and jerk, due to the friction of rest in the stuffing boxes, the increased mass and other causes, increases to such an extent as to introduce serious disadvantages. One purpose of this invention is to reduce materially these disadvantages, by feeding the water to the boiler through two or more valves, thereby reducing the capacity of each valve materially, somewhat according to the number used, and thus reducing the undesirable effect of the sticking and jerking tendency of each materially. At the same time the method of feeding is such that the valves may be arranged so as to act, ordinarily, successively rather than simultaneously, one being substantially closed while another is substantially fully open, so that simultaneously sticking of the valves is not likely to occur.

It has also been found in practice that as refinements are introduced more and more into boiler practice, more refined methods of control of the feed water are desired than is possible by the use of the ordinary systems of control. Hence a further object of this invention is to increase the sensitiveness of the possible adjustments of the feed-water control and thus to increase the possible refinements in practice. This result is obtained by the use of specially designed feed-water valve ports, and by the use of a plurality of feed-water regulators, instead of one as has previously been the practice, so that the valves or the adjustments of the regulators may be unlike, thus causing corresponding differences in the flow of water at particular water levels or under particular conditions of loads.

Other objects of the invention will be ap-

parent upon a consideration of the drawings attached hereto and the description of the invention contained herein.

Of the accompanying drawings Figure 1 is introduced merely to illustrate the operation of the particular form of regulator which I prefer, and it is an elevation of a boiler with such a regulator attached thereto. Fig. 2 is an elevation of a boiler with a system of regulators attached thereto which embodies the features of my invention. Fig. 3 is a special form of valve used with one of the regulators. Fig. 4 is a special form of valve used with the other regulator. Fig. 5 is a diagrammatic view of two regulator tubes showing the position of each with reference to the various levels of water in the boiler. Figs. 6, 7 and 8 are curves showing the relation of the flow of water into the boiler to the boiler level.

Although any suitable type of feed-water regulators may be used, yet, for the purposes of illustrating my invention I prefer the type which is fully shown and described in my said co-pending application Serial No. 793,159, and which is operated according to the method fully described in Patent No. 1,148,483, issued to me July 27, 1915. In general the method described in said patent consists in producing a continuous and constant flow of water into the boiler so long as the load is constant; in causing the change in inflow to lag behind the change in outflow when the load is changing, but to gradually become equal to the outflow when the load becomes constant no matter what the load may be; so that for every different load, so long as the load is constant, a different constant water level corresponding to the particular load is maintained. By this method heat energy is stored in the boiler during decreasing and light loads; and by carrying out this method in a definite unvarying and dependable manner the hazards incident to boiler use are decreased and the capacity and the economy of the boiler are materially increased.

Although my invention consists in the use of two or more regulators on the same boiler, yet, in order to fully explain the operation of the regulators I have shown in Fig. 1 a single regulator such as is shown in my said copending application, and the operation of which is as follows: The boiler is indicated by the reference number 4. The normal or

average water level in the boiler is indicated by the dotted line 5, the minimum permissible water level is indicated by the dotted line 6, and the maximum permissible water level by the dotted line 7. The feed-water regulator in this instance comprises an expansion tube 8 mounted on the supports 9 and 10, which are fixed in any suitable manner to the T-base 11. The base 11 is supported in any suitable manner in such a way as to bring the central portion of the operative portion of the expansion tube 8 in substantially the same horizontal plane as the normal water level in the boiler; the lower end of the operative portion of the expansion tube at about the same elevation as the minimum permissible water level, and the upper end of the operative portion of the expansion tube at about the same level 20 as the maximum permissible water level.

Pivoted to the upper end of the support 10 by means of the pin 13, or in any other suitable manner, is a lever 15. The upper end of the expansion tube 8 is pivoted at 25 the point 12 to the short arm of the lever 15; and connected to the outer end of the long arm of the lever is any suitable member, such as a rod 17, which supports a long arm 18 of a second lever 19. The lever 19 is adapted to operate the feed water valve 20 of the supply pipe 21. Pressure may be applied to the water in the supply pipe in any suitable manner. A weight 14 eliminates at all times any loose play in the connection between the expansion tube 8 and the lever 19, and also causes the valve to operate, when allowed to do so, by the contraction of the expansion tube 8.

The location of the upper end of the expansion tube 8, with reference to the fulcrum 13 of the lever 15, may be adjusted by means of nuts 16; and the relation of the opening of the valve 20 to the outer end of the long arm of the lever 15 may be adjusted 40 by means of nuts 23. Braces 26 fixed to the base 11 prevent buckling of the expansion tube. A consideration of the apparatus described will show that, as the expansion tube expands, the outer end of the long arm 45 of the lever 15 will be raised, the weighted arm of the lever 19 will be raised and the valve 20 will be opened.

The lower end of the expansion tube 8 is connected to the boiler at or below the minimum permissible water level of the boiler by means of the pipe 27; and the upper end of the expansion tube is connected to the boiler at or above the maximum permissible water level by means of the pipes 28 and 29; 55 so that water from the boiler can pass freely into the lower end of the expansion tube, and steam from the boiler can pass freely into the upper end of the expansion tube. As a consequence of this manner of connecting 60 tube 8 to the boiler, the elevation of the

water in the tube will depend upon the elevation of the water in the boiler; and the upper end of the tube which contains steam will be at substantially the same temperature as the steam in the boiler, while the 70 lower end of the tube which contains water will be at a lower temperature. Even though the water when it enters the tube may be of substantially the same temperature as the steam, yet it will rapidly radiate 75 heat and cool to a lower temperature; and as there is no material interchange of the water in the tube and in the boiler, the water in the tube will necessarily be substantially 80 at all times somewhat materially lower in temperature than the water or the steam in the boiler.

Now, it is evident, that under these circumstances, as the water level in the boiler varies, the amount of the water in the tube 85 will vary correspondingly and the tube will expand or contract. The valve 20 will then be opened more or less and more or less water will pass into the boiler, offsetting more or less the tendency of the water level 90 in the boiler to vary. There will thus be a tendency to maintain uniform the elevation of the water level. However, by the use of an expansion tube of proper length or coefficient of thermal expansion, or by suitable 95 levers or valve ports, or in any other suitable manner, the variations in the valve openings due to changes in lengths of the expansion tube may be sufficiently slight, so that in case of a heavy load on the boiler 100 the inflow of water will be less than the consumption of water, and the water in the boiler will sink. On the other hand, by such means, in case of a light load the inflow may be made greater than the consumption of 105 water and the water will rise.

Hence, by the use of this regulator, it will be found that, not only is there a continuous feed to the boiler at all times when the boiler is under load, but, instead of the variations in feed being coincident and equal to the variations in steam requirements, there is a predetermined amount of lag in the variations in feed which relieves the boiler at times of heavy loads and allows the 115 storage of heat energy during periods of light loads. The arrangement is also such that in case of a very light load or no load, the feed valve will be nearly or entirely closed, and when heavy loads are long continued or excessive the inflow becomes equal to the outflow, and sufficient water is thereby insured. In fact, at any time when the load becomes constant, whether light, heavy or intermediate, the level will become constant at a point depending upon the amount of load, each load on the boiler having its corresponding water level.

In Fig. 2 of the drawings I have shown the preferred form of my complete system. 130

The boiler casing 32 has mounted thereon in an ordinary manner a cross drum 33. The boiler is fed by means of the pipes 34 and 35 controlled respectively by the regulators 5 36 and 37 acting respectively on valves 38 and 39. The regulators, in this instance, are operatively connected to the drum through the water columns 40 and 41 by means of the pipes 42, 43, 44 and 45.

10 By the use of this system, it is evident that the inflow will be affected by the water level at each end of the drum; and that the end of the drum having the lower water level will receive the greater inflow of water, 15 and hence the levels will tend to become more uniform.

In the application to a boiler of the two regulators, as herein shown, I prefer to arrange the apparatus so that one of the regulators 20 holds its valve wide open during substantially all of the time that the water level is below the average; and the other regulator holds its valve closed during substantially all of the time that the water level 25 is above the average. To produce this result I mount the expansible tube 36 Fig. 5 so that the upper end of the operative portion of the tube is substantially at the same elevation as the maximum water level, which 30 is indicated by line 47 Fig. 5, and the lower end of the operative portion of the tube is a little below the average water level which is indicated by line 48, and I mount the tube 37 so that its lower end is substantially at 35 the same elevation as the minimum desired water level, indicated by line 49, and its upper end is a little above the average water level.

The operation of the system is as follows: 40 When the boiler is carrying an average constant load, the water level in the boiler will be at line 48, tube 37 will be nearly full of water, and it will therefore be cool and contracted, and valve 39 will therefore be nearly closed. Tube 36 will be substantially full of steam, and it will therefore be expanded, and valve 38 will be open nearly to its maximum extent. So long as there is no change in the amount of steam used there will be 45 no material change in the amount of water in the boiler, and the valves will be unchanged. If, however, the water level lowers a material amount because of greater load on the boiler, or otherwise, valve 38 will 50 open wide and valve 39 will open more; and from that point until the minimum water level is reached the control of the water level will be due to the action of the tube 37 upon valve 39. If, on the other 55 hand, the water level should rise materially above the average water level valve 39 would close entirely, and the entire control of the water level will depend upon tube 36 and its corresponding valve 38.

60 It will thus be seen that, ordinarily, at

water levels somewhat below the average, the entire control of the inflow depends upon the action of tube 37; and, ordinarily, at water levels somewhat above the average, the entire control depends upon the action 70 of tube 36. As a consequence, during the greater portion of the time one valve only is operated, and the undesirable effects due to the sticking and jerking of one large valve are reduced by the use of two valves each substantially only one-half as large as one large one would necessarily be. If it is desirable to 75 reduce to a minimum the disadvantage of the simultaneous jerking of the valves the range of the simultaneous action of the two 80 regulators may be substantially eliminated by lowering one regulator tube entirely below and raising the other one entirely above the average water level. On the other hand if it is desired to reduce the unequal distribution of the water in the boiler the simultaneous action of the two valves may be 85 materially increased; and, in fact, if desired, may be substantially continuous, by placing the two regulators at substantially the same 90 elevation.

As hereinabove suggested, another object of my invention is to increase the possibilities of greater refinement in the feeding of water to boilers, and one application of my 95 invention to produce this result is as follows: As is explained hereinabove the action of the regulator, by suitable arrangements and adjustments, will lag behind the changes in the level of the water in the 100 boiler, so as to cause the level of the water to sink as the load increases, or to rise as the load decreases, within certain maximum and minimum limits. It is evident that with a single regulator the amount of lag or the 105 time of the lag will not vary materially at different water levels. In other words the lag of a single regulator would be substantially the same, with a large load and low water level as with a light load and high 110 water level. In practice however it is sometimes desirable to reduce the time or the rate of lag with large loads on the boiler below the time or rate with small loads on the boiler. One reason for this is because the 115 danger from variations in water levels is greater with a large consumption of steam than with a small consumption of steam. With my system, it will be apparent that this may be readily cared for, as it is necessary only to change the structures or the arrangements of the regulators so that the regulator controlling the variations during times of heavy loads will have a lag corresponding to that desired for a heavy load, 120 while the regulator controlling the variations during times of light loads will have a different lag but one such as is desired at such times.

To produce this result I have, as indi- 130

cated by Fig. 5, shown the expansible tube 37 more nearly horizontal than tube 36 and somewhat longer, so that it will be more sensitive to variations in water levels, and hence will more quickly respond to such variations in its action on valve 39. To further assist in this I have shown the leverage between the tube 37 and the valve 39 materially greater than is the case with the leverage between tube 36 and valve 38. Because of this also the action of the regulator 37 is more sensitive and the lag in time and the lag in rate of inflow with reference to the changes in outflow will be reduced. It will readily be understood, that other similar variations or refinements may be taken care of by the use of more than two regulators.

Other refinements with reference to the relative inflow and outflow of the boiler, or of the relation of the water level therein to the load on the boiler, are sometimes desired. I have made further provision in my system for such refinements in the following manner: Ordinarily the rate of inflow through a valve is substantially proportional to the valve opening. Although any suitable valve may be used, yet I prefer, for this particular refinement in feeding boilers, valve 38 of which Fig. 3 shows an enlarged cross section. From this, it is evident, that the flow through the valve ports will be substantially proportional to the distance the valve cylinder is moved from its seating position, as the ports have parallel sides so that the opening therethrough is proportional to the length. With such a valve the lag of the inflow with reference to changes in level will be substantially the same for all positions of the valve cylinder, as this lag will depend only upon the lag of the movement of the cylinder, and hence will depend only upon the leverage and other features of the regulator which would affect the opening substantially uniformly at whatever position the cylinder might be.

However, various means may be used for controlling the inflow in a manner unlike the variations of the valve movement, and in a manner unlike the variations in the expansion or contraction of the expansion tube. I prefer in order to produce this result to vary the shapes of the ports of the feed water valves. As indicated in Fig. 4, which is an enlarged cross section of valve 39, the ports of the valve do not have parallel sides; so that the inflow through the ports is not in proportion to the distance of the cylinder from its seat. As a consequence of the special form of ports shown, the flow through the ports will increase at a greater rate than the rate in which the cylinder is moved from its seat. By the use of this valve to control the flow of water through pipe 35 it is evident that the inflow due to this valve will vary with reference to variations in the

water level in a manner unlike the variations due to valve 38 which has ports with parallel sides. As a consequence of this special arrangement of the regulator tubes hereinabove described, the inflow of water while the water is materially lower than the average, so that regulator 37 is operating, will increase at a rate materially greater than the rate at which the valve is opening. One object of this specific arrangement is to be sure of a sufficient inflow when the consumption of steam is great and the level of water in the boiler is low. At the same time while the load is light and regulator 36 is effective in controlling the flow the lag in the inflow will be greater, and the inflow will be substantially proportional to the opening of the valve. It is of course understood, however, that any suitable form of valve or valve ports may be used, and I do not wish to be confined to the particular form herein described.

Also it may be desired to maintain the elevation of the water level in some portions of the boiler somewhat unlike the elevations in other portions. In this illustration of my invention I have shown valve 39 and pipe 35 larger respectively than valve 38 and pipe 34. As a consequence the water level adjacent the inlet of pipe 35 will be somewhat higher than that adjacent the inlet of pipe 34 when both regulators are in full operation. As the water level rises, however, and valve 39 closes the water level will become more nearly uniform throughout; and, if properly adjusted, during the average load on the boiler the water level will be substantially uniform. As the water rises still higher however, and valve 39 closes entirely, the water level adjacent the inlet of pipe 34 will have a somewhat higher elevation than that adjacent the other end of the drum. So that, in general, with low levels and heavy loads the water level adjacent the right hand end of the drum will be higher, and during light loads and high water levels the water level adjacent the left hand end of the drum will be higher. It is evident from the foregoing that, by suitably positioning and adjusting the regulators, and properly selecting the sizes of the feed pipes and the valves, the relative elevations of the water levels adjacent the inlets may be varied as desired.

Figs. 6, 7, 8, show, diagrammatically, the relation of the inflow of water to the water level in the particular system which I have selected to illustrate my invention. In these figures the abscissæ indicate the elevation of the water in the boiler in inches above some arbitrary point, and the ordinates indicate the inflow of water in pounds per minute. In Fig. 6 the curve 50 shows the relation of the inflow to the water level as it would be if controlled by the regulator 36 alone; in Fig. 7 the curve 51 shows the relation as it would

be if controlled by regulator 37 alone; and in Fig. 8 the curve 52 shows the relation as controlled by the two regulators in the manner hereinabove described. For instance the 5 dotted prolongation of the straight portion of curve 52 shows the effect of regulating 36, and the total flow at a water level elevation of two inches is the sum of the effects of the two regulators. The curves 10 shown are not intended to be definite, but are merely suggestive; and it is evident that, by various modifications in the structure and adjustments of the regulators, the relation of the inflow to the water levels might be 15 varied indefinitely.

Although I have described with much particularity the specific feed-water regulator system which I prefer, yet I wish it understood that other types and forms of feed 20 water regulators may be used, and various other modifications in the system, may be made by those skilled in the art to produce substantially the same results without departing from the scope of my invention as 25 disclosed by the following claims.

I claim as my invention

1. A method of feeding water to boilers consisting in causing the inflow to substantially equal the outflow while the load is 30 constant, in causing the rate of change of the inflow to lag behind the rate of change of the outflow while the outflow varies, and in causing the amount of said lag at certain water levels to be unlike the amount at other levels. 35 2. A method of feeding water to boilers consisting in causing the inflow to substantially equal the outflow while the load is constant, in causing the rate of change of the inflow to lag behind the rate of change of the 40 outflow while the outflow varies, in causing the relation of the inflow to the outflow to be always the same under similar load conditions, and in causing the amount of said lag at certain water levels to be unlike the 45 amount at other levels.

3. A method of feeding water to boilers consisting in causing the inflow to substantially equal the outflow while the load is constant, but in causing the change in rate 50 of inflow to lag behind the change in rate of the outflow when the rate of outflow varies, and in causing the amount of the said lag to vary at different water levels.

4. A method of feeding water to boilers 55 consisting in causing the rate of change in the inflow to lag behind the rate of change of the outflow while the outflow varies, and in causing the amount of said lag at one load to be greater than the amount of said 60 lag at another load.

5. A method of feeding water to boilers

consisting in causing the change in rate of the inflow to lag behind the change in rate of the outflow when the rate of outflow varies, and in causing the amount of said lag 65 to vary as the load varies.

6. A method of feeding water to boilers consisting in passing water into a boiler at two remote points, at a rate depending upon the water level in the boiler at two 70 points located a material distance apart, and in causing the rate of change of the total amount of water passing into the boiler to lag behind the rate of change of the amount passing out of the boiler. 75

7. A boiler feed water system comprising two regulators, each of said regulators being connected to said boiler above and below the average water level, one of said regulators being at a higher elevation than the 80 other regulator.

8. The combination of a boiler and two feed-water regulators: each of said regulators being operatively connected to said boiler; each of said regulators comprising 85 an expansion tube, each of said tubes being inclined at an angle to the horizontal plane, and one of said angles being greater than the other.

9. A combination of a boiler, two water 90 regulators, two valves and two levers; each of said regulators being operatively connected to said boiler and to one of said valves; each of said levers operatively connecting one of said regulators with one of 95 said valves; the leverage of one of said levers being greater than the other.

10. A method of feeding water to boilers consisting in causing the rate of change of the inflow to lag behind the rate of change 100 of the outflow while the outflow varies, and in causing the amount of said lag at light loads to be greater than the amount of said lag at heavier loads.

11. A method of feeding water to boilers 105 consisting in causing the rate of change of the inflow to lag behind the rate of change of the outflow while the outflow varies, and in causing the amount of said lag to gradually increase as the load decreases. 110

12. A method of feeding water to boilers consisting in causing the rate of inflow to the boiler with reference to the rate of outflow therefrom to gradually increase as the outflow increases. 115

In testimony whereof, I hereunto set my hand in the presence of two witnesses.

ROGER W. ANDREWS.

In the presence of—

E. W. NICK,

V. V. VEENSCHOTEN.
